UNITED STATES PATENT OFFICE.

PETER LEE FERGUSON AND JOSEPH W. WHEELWRIGHT, OF OGDEN, UTAH.

ILLUMINATED SIGN.

1,076,566.

Specification of Letters Patent.

Patented Oct. 21, 1913.

Application filed September 13, 1912. Serial No. 720,232.

To all whom it may concern:

Be it known that we, PETER LEE FERGUSON and JOSEPH W. WHEELWRIGHT, citizens of the United States, residing at Ogden, in the county of Weber and State of Utah, have invented new and useful Improvements in Illuminated Signs, of which the following is a specification.

The invention relates to signs and has for 10 an object to provide an illuminated sign.

The invention relates more particularly to signs used in connection with vehicles such as automobiles or motorcycles for permanently displaying the number of the vehicle in the night season.

The invention consists primarily of a box-like structure having stencil characters representing the number of the vehicle thereon, the mentioned structure being mounted on 20 the vehicle adjacent the tail-light thereof, with means on the structure for connection with the tail-light whereby the stencil characters on the structure will be illuminated when connection is made with the light.

25 In the further disclosure of the invention reference is to be had to the accompanying drawings, constituting a part of this specification, in which similar characters of reference denote corresponding parts in all the 20 views, and in which:

Figure 1 is a front elevation of the device, showing the flexible hood in connected position; Fig. 2 is a plan view showing the flexible hood in connected position in full lines 35 and in disconnected position in dotted lines; Fig. 3 is a horizontal sectional view taken on the line 3—3 in Fig. 1; Fig. 4 is a vertical transverse sectional view taken on the line 4—4 in Fig. 1; and Fig. 5 is a vertical transverse sectional view taken on the line 5—5 in Fig. 1.

Referring more particularly to the views, we employ a casing 10 having the front thereof open, a suitable clamp 11 being extended from the rear side of the casing and encircling an upwardly extending arm 11^a formed at one end of a bracket 11^b supported on a bearing 11^c, secured to the rear of a vehicle, the other end of the bracket 50 11^b being bent upwardly to form an arm 11^d as shown in Fig. 2, the mentioned arm 11^d being similar to the arm 11^a with a screw 11^e passing through the clamp 11 and engaging the arm 11^a to rigidly secure the 55 clamp thereto, thus supporting the casing 10

rigidly on the rear of the vehicle. A series of vertically extending H-shaped members 12 are arranged in spaced relation to extend across the front of the casing, the said H-shaped members being secured to the upper 60 and lower walls of the casing and forming slides 13 for slidably receiving number plates 14 as shown in Fig. 3, the said number plates being independently removable from the casing and of a stencil nature, the 65 characters or numbers being cut out of the plates so that when the interior of the casing 10 is illuminated the numbers will be readily visible. The number plates 14 are preferably stamped from sheet material and each has formed at the upper end thereof an apertured flange 15, spaced ears 16 being mounted on the upper wall of the casing 10 and provided with apertures adapted to register with the apertures of the flanges 15 when the number plates 14 are mounted in 70 position on the casing 10, bolts 17 being passed transversely through the registering apertures of the flanges 15 and ears 16 to 75 secure the number plates 14 in rigid position on the casing, it being readily understood that the flanges 15 also form holders or handles whereby, when the bolts 17 are removed from the flanges and ears, the number plates can be readily removed from the 80 casing 10, it being further seen that the lower ends of the number plates abut against the lower wall or bottom of the casing, thus limiting the downward sliding movement of the number plates on the casing. 90

An opening 18 is formed in one end 19 of the casing 10 and formed with the end 19 and encircling the opening 18 is an outwardly projecting circular flange 20 adapted to be encircled by the inner end of a flexible hood 21, the said hood being rigidly secured to the flange 20 by a band 22 arranged to encircle the inner end of the flexible hood 21 after the same has been mounted to encircle the flange 20, the ends of the said 100 band 22 being bent laterally to receive a screw 23 transversely therethrough so that the band can be rigidly clamped in position to secure the inner end of the hood. The hood 21 is preferably made of asbestos cloth 105 or the like, and mounted on the outer end of the hood is a spring-like ring 24, constituting a securing member, for securing the outer end of the hood to a bull's eye 25 of a tail-lamp 26, said tail-lamp being of any 110

preferred construction and having the usual red glass facing rearwardly, constituting a danger signal.

The tail-lamp 26 is provided with a clamp 5 26^a encircling the arm 11^a and rigidly secured thereto by a screw 26^b having connection with the clamp 26^a and engaging the arm 11^a as shown, it being thus seen that the casing 10 and tail-lamp 26 are supported on the single bracket 11^b.

It will now be seen that when it is desired to illuminate the casing 10 to display the characters on the plates 14, the outer end of the flexible hood 21 is slipped over the bull's eye 25, the said hood being retained in clamping engagement with the bull's eye by the spring-like ring 24, the mentioned hood being preferably made flexible so that the same can be readily disconnected from the bull's eye and also to permit the lighting of the tail-lamp 26 without disturbing the casing 10, particularly when the bull's eye is mounted to swing on the tail-lamp and constitutes the closure therefor. The interior 25 of the casing 10 is preferably painted white to form a suitable reflector so that when the hood is connected to the tail-lamp in the manner mentioned, the characters on the number plates 14 will be illuminated so 30 as to be clearly visible. By mounting the number plates independently on the casing 10, the same can be independently removed for the purpose of changing the numbers or

inserting new number plates, and by referring to the views it will be noted that each 3 number plate is independently secured in rigid position on the casing by means of the bolts 17, in the manner mentioned herefore.

Having thus described our invention, we claim:

1. In combination, a hollow sign, an illuminating member for the sign, and disposed in longitudinal alinement therewith, a flexible hood circular in cross section secured to the sign and illuminating member, said hood directing the light rays from the illuminating member to the interior of the sign.

2. In combination, a hollow sign having 56 an open end, an illuminating member for the sign disposed in longitudinal alinement with the open end thereof, and a flexible hood having one end secured to the open end of the sign and its other end secured to the illuminating member, said hood directing the light rays from the illuminating member into the open end of the sign.

In testimony whereof we affix our signatures in presence of two witnesses.

PETER LEE FERGUSON.
JOSEPH W. WHEELWRIGHT.
